UNITED STATES PATENT OFFICE.

ROSANNA DU FORA ULMAN, OF AURORA, ILLINOIS, ASSIGNOR TO INTERNATIONAL CORSET COMPANY, OF AURORA, ILLINOIS, A CORPORATION OF ILLINOIS.

COMBINATION CORSET AND BRASSIÈRE.

Application filed June 22, 1927. Serial No. 200,680.

This invention relates to a combination corset and brassière. The corset portion is adapted to confine the body of the wearer at and below the waist line, and the brassière 5 is connected thereto only at the front,—the sides and back of the brassière being free. The brassière is adapted to encircle the body of the wearer above the waist line, and the sides and back thereof, when the garment is 10 in position, are substantially above the top of the corset member.

One of the objects of my invention is to provide a combination garment which may be worn with the same degree of freedom as 15 is derived from separate hip confiners and "bandettes", but which will obviate the objections attending the use of separate garments, particularly the tendency of the flesh of the wearer to bulge out at the front between the top of the corset and the lower margin of the brassière or "bandette".

My improved combination garment provides a firm, smooth, uninterrupted support 25 for the front of the body and prevents bulging, without detracting from the ability of the wearer to move the body and arms unrestrainedly.

In the drawings:

Figure 1 is a front view of the garment, arranged as in use.

Figure 2 is a back view of the same.

Figure 3 is a plan view of the inside of the garment with certain parts broken away to more clearly show the construction.

Referring now to that embodiment of my invention shown in the drawings, the corset member is indicated as a whole at A and the brassière at B. The corset A is of the hip confiner type adapted to confine the body at and below the waist line, and may be of any desired construction. As shown, the back of 40 the corset is composed of two non-elastic sections 1, 1 and an elastic section 2 therebetween, reinforced by a non-elastic piece 3 stitched thereto. Said sections 1 and 2 are connected together longitudinally.

Connected to each of the back sections 1 is a non-elastic front member 4, and connected to one of the front members 4 is a non-elastic 50 center front panel 5, which, preferably, is formed with an integral part 6 extending upwardly above the body of the corset A. As shown, the extension 6 has two curved side margins 7, and it is narrower at its

upper end than where it merges into the 55 panel 5.

The free longitudinal margin of the front panel 5 is provided with hooks 8 for attachment to eyes 9 on the free margin on the front member 4. I have shown certain desirable features of construction such as elastic portions 10 in the front members 4 near the waist line, and elastic 11 in the lower part of the front panel 5, but, as stated, the exact construction of the corset A herein shown may be varied without departing from the scope of my invention. The usual garter straps are indicated at 12.

The brassière B may be of one piece of fabric, but as shown, it comprises a front 13 and two back pieces 14 connected to the side margins of the front 13. The front 13 has greater vertical width at its center than at its ends, the cutting away indicated at 15 being instrumental in narrowing the front 75 13, as desired, for connection to the relatively narrow back sections 14, and to cause the sides and back of the brassière to fit the body of the wearer substantially above the upper margin of the corset A, so there will be a 80 space between the lower margin of the brassière (except at the center front), and the top margin of the corset. The two back sections 14 are adapted to be connected together at the back of the wearer by hooks and 85 eyes 15 and 16, respectively. Familiar shoulder straps 17 are provided.

The extension member 6 is adapted to overlie part of the brassière section 13, and is stitched thereto at its curved margins 7. 90 The lower margin 18 of the part 13 may be stitched to the front panel 5 where it merges into the extension 6 of the corset A. This construction is neat and workmanlike, but obviously the part 13 may be made in two 95 pieces and that portion which underlies the extension 6 could be eliminated.

Attached to the longitudinal margins of the front panel 5 on the inner side thereof, is a loose shield 19 reinforced by boning 20. The 100 shield extends over the abdomen of the wearer and slightly above the waist line and the line 18 where the lower edge of the brassière is connected to the panel 5. This shield assists in maintaining the straight front and 105 smooth line from the top of the extension 6 to the bottom of the panel 5.

Various modifications in details of con-

struction may be made without departing from the scope of my invention and I do not desire to be limited to the particular form herein shown and described, except as set forth in the appended claim.

I claim as my invention:

A combination garment, comprising a corset, and brassière permanently connected to the corset at the front in line with the upper edge thereof for a substantial circumferential extent, said brassière having its lower edge inclined upwardly and rearwardly from

its connection with the upper front edge of the corset adjacent each side of the garment to the center of the back, whereby bulging out of the wearer's body above the upper front line of the corset is prevented and freedom of body movement between the sides and back of the corset and brassière portions of the garment is permitted.

20

In testimony, that I, claim the foregoing as my invention I affix my signature this 20th day of June, 1927.

ROSANNA DU FORA ULMAN.
